UNITED STATES PATENT OFFICE.

GEORGE REZNOR, OF MERCER, PENNSYLVANIA.

PLUMBER'S HOOK.

SPECIFICATION forming part of Letters Patent No. 501,484, dated July 11, 1893.

Application filed April 12, 1893. Serial No. 470,013. (No model.)

To all whom it may concern:

Be it known that I, GEORGE REZNOR, a citizen of the United States, residing at Mercer, in the county of Mercer and State of Pennsylvania, have invented certain new and useful Improvements in Plumbers' Hooks for Fastening Gas and Water Pipes, of which the following is a specification, reference being had therein to the accompanying drawings.

This invention has relation to that class of devices known to the trade as "plumbers' hooks," which are used to secure gas and water-pipes in the various positions necessary in a building. Heretofore these hooks have been made of forged metal, which is unnecessarily costly and produces an inferior article, and it is the object of this invention to provide an improved form of hook which may be readily formed of a single piece of wire and which will be cheaper and stronger and more practical than the old forged hooks, as more fully hereinafter set forth.

In the drawings Figure 1 is a side elevation of the preferred form of hook, and Fig. 2 is a sectional view of a portion of a structure showing the manner of using the hooks, the hook shown at the right hand side of the figure being a slight modification.

The form of hook herein shown is adapted particularly for securing the pipes in corners, either vertically or horizontally, as shown at the right of Fig. 2, but it is evident that it may be used to hold them to the ceiling and in various other positions. As shown in the drawings this hook is formed of a single piece of wire which may be bent into shape by suit-

able tools or machinery. It is formed into a curved part *a*, which is substantially semi-circular and receives the pipe, and a single prong *a'* sharpened to enable it to be driven 40 into the adjoining wood-work. To provide a rigid and strong impact-shoulder, to enable it to be driven into the wood easily and without injury, the wire at the junction of the prong and curved part is formed into a closed eye 45 *a''*, which projects out from the prong on the opposite side from the curved part. This eye, being quite small, is very rigid and is easily struck by the hammer in driving.

Instead of making a closed loop for the 50 driving shoulder, a rigid shoulder may be formed by bending into a loop *a'''* having a substantially S-form, as shown at the right of Fig. 2.

This hook will be strong and durable and 55 easily driven home without bending and it may be manufactured at much less cost than the old-style forged hook.

Having thus fully described my invention, what I claim is—

A plumber's hook consisting of a single piece of wire bent into a curved open supporting-part *a* and a straight prong *a'*, a lateral impact shoulder being formed at the juncture of said two parts by bending the 65 wire into a loop, substantially as described.

In testimony whereof I affix my signature in presence of two witnesses.

GEORGE REZNOR.
